UNITED STATES PATENT OFFICE.

WILLIAM S. GOULD, OF NEW YORK, N. Y.

SEPARATOR FOR STORAGE-BATTERY PLATES.

1,195,924.

Specification of Letters Patent. Patented Aug. 22, 1916.

Application filed March 14, 1914. Serial No. 824,605.

To all whom it may concern:

Be it known that I, WILLIAM S. GOULD, a citizen of the United States, and a resident of the city, county, and State of New York, have invented certain new and useful Improvements in Separators for Storage-Battery Plates, of which the following is a specification.

My invention relates to separators for storage battery plates, and in its broadest aspects, has to do with a composite separator of which a portion is porous to the electrolyte and has the necessary insulating qualities, while another portion is inert to the electrolyte and therefore gives strength to the separator and maintains it in position during its use in the battery.

Specifically, the invention relates to a separator which comprises a sheet of wood which is more or less acid deteriorating, smooth on one side and provided with ribs on the other, and of a perforated member which is inert to the electrolyte, and which has ribs on one side thereof, while it is smooth on the other side.

I will set forth in detail one embodiment of my invention in the following description taken in connection with the attached drawings, in which—

Figure 1 shows a wood member in elevation; Fig. 2 shows a rubber member in elevation; and Fig. 3 shows a section of the separator.

The separator comprises a perforated rubber sheet 1 with vertical ribs on one side, as shown in Fig. 2, and a wood member 2, also with ribs 4 on one side, as shown in Fig. 1. The ribbed sides of the two are placed together so that the ribs of each are on the inside of the couple. The flat side of the rubber sheet is preferably placed against the positive plate and the flat side of the wood sheet against the negative plate.

This arrangement may be reversed, but that described is preferable. The ribs of the two sheets are staggered relatively to each other so that the ribs of rubber engage the web of the wood, and the ribs of wood engage the web of the rubber sheet, as all the ribs project from the sheets about the same distance. The mechanical separation is maintained by the rubber ribs, that is, while at the beginning the separation is effected equally by both sets of ribs, the rubber ones are durable and maintain the desired separation, so that should the battery plates buckle

the rubber sheet will positively prevent them coming together to produce a short circuit between them. The wood ribs are mainly for the mechanical strength of the wood itself prior to the time it is placed in the cell. The wood ribs, however, also perform the function of maintaining the acid spaces between the wood and rubber and of holding both wood and rubber flat against their respective plates, the wood sheet serving to hold the spongy or active material in place at all points while still permitting of access of the electrolyte thereto at practically all points because of the porous character of the wood.

By the use of my invention the strength and durability of a rubber separator are secured while the impervious-to-battery-sediment or superior insulating qualities of wood are also secured. Preferably, the holes in the rubber sheet are smaller in diameter than the separation distance between the wood and rubber webs and as that separation distance is maintained by the rubber ribs any sediment that works through the holes will fall away in the wider acid channel without any deleterious effect on the cell.

Having described my invention, what I claim as new and desire to secure by Letters Patent is:—

1. A separator for storage battery plates, comprising a perforated hard rubber sheet having a flat face to be placed against the positive plate and a porous wood sheet having a flat face to be placed against the negative plate to hold the spongy material thereof in place, said wooden sheet having ribs for spacing it from the rubber sheet to provide circulation channels between the separator sheets and hold them flat against the battery plates.

2. A separator for storage battery plates comprising a perforated hard rubber sheet having a flat face to be placed against one battery plate and a porous wood sheet having a flat face to be placed against the other battery plate, said rubber sheet having reinforcing ribs for spacing it from the wooden sheet to provide circulation channels between the separator sheets and hold them flat against the battery plates.

3. A separator for storage battery plates comprising a perforated hard rubber sheet placed adjacent the positive plate and a porous wood sheet having a flat face placed against the negative plate to hold the spongy

- material thereon in place, said rubber sheet having vertical reinforcing ribs.
4. A separator for storage battery plates comprising a porous wood sheet, having a substantially flat face adapted to be placed against the active material of one of the battery plates to hold it in place and a hard rubber sheet adapted to be interposed between the wood sheet and the other battery plate, and adapted to prevent short circuits between the plates due to their buckling and hold the wood sheet in position.
5. A separator for storage battery plates comprising a sheet of porous material pervious to the electrolyte, adapted to be placed against the active material of one of the battery plates to hold it in place and a sheet of hard insulating material having openings therein and adapted to be interposed between the sheet of porous material and the other battery plate, and adapted to prevent short circuits between the plates due to buckling.
- 10 6. A separator for battery plates comprising a sheet of flexible porous material pervious to the electrolyte, and a perforated sheet of hard insulating material, one of said sheets having ribs for spacing the body portions of the sheets from one another, and holding the porous sheet flat against the active material of one of the battery plates and said sheet of insulating material being adapted to prevent short circuits between the plates due to buckling.
- 15 7. A separator for battery plates comprising a sheet of flexible porous material pervious to the electrolyte, and a perforated sheet of hard insulating material, said sheets having spaced apart ribs for holding the body portions of the sheets in position spaced from one another, the number of ribs on the porous sheet being greater than the number of ribs on the sheet of insulating material.
- 20 8. A separator for battery plates comprising a sheet of flexible porous material pervious to the electrolyte, and a perforated sheet of hard insulating material, one of said sheets having ribs for spacing the body portions of the sheets from one another, and holding the porous sheet flat against the active material of one of the battery plates, the diameter of the perforations in
- the sheet of insulating material being less than the distance across the space between the body portions of the sheets.
- 25 9. A separator for battery plates comprising a hard rubber sheet and a porous wood sheet, both flat on the outside where they engage the plates, and spaced from one another to provide circulation space for the electrolyte therebetween and said rubber sheet having strengthening ribs to prevent short circuits between the plates due to buckling.
- 30 10. A separator for storage battery plates comprising a sheet of porous material pervious to the electrolyte adapted to be placed against the active material of one of the battery plates and a sheet of hard insulating material adapted to be interposed between the sheet of porous material and the other battery plate, said sheet of insulating material being provided with ribs at its edges which prevent the buckling of the battery plates from causing short circuits between the plate and also space the body of the insulating sheet from the porous sheet.
- 35 11. A separator for storage battery plates comprising a porous wood sheet pervious to the electrolyte adapted to be placed against the active material of one of the battery plates and a perforated hard rubber sheet adapted to be interposed between the wood sheet and the other battery plate and adapted to prevent short circuits between the plates due to buckling.
- 40 12. A separator for storage battery plates comprising a sheet of porous material pervious to the electrolyte, adapted to be placed against the active material of one of the battery plates to aid in holding it in position, and a sheet of hard insulating material adapted to be interposed between the sheet of porous material of the other battery plate, to prevent buckling of the plates from causing short circuits, each sheet being provided with ribs extending toward the other sheet, to hold said sheets in proper spaced relation.
- 45 In testimony whereof, I have signed my name to this specification, in the presence of two subscribing witnesses.
